(57) **CLAIM**

The ornamental design for an optical disc recording device, as shown and described.

DESCRIPTION

FIG. 1 is a top perspective view of an optical disc recording device showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a top perspective view thereof, wherein the tray is open.

The broken line showings are for the purpose of illustrating unclaimed portions of the optical disc recording device and form no part of the claimed design.
